B. F. FOWLER,
MEANS OF SEDIMENT DRAINAGE,
APPLICATION FILED MAR. 24, 1918.

Patented Apr. 20, 1920.

INVENTOR.

UNITED STATES PATENT OFFICE.

BEN F. FOWLER, OF MIDIAN, KANSAS.

MEANS OF SEDIMENT-DRAINAGE.

1,337,215.

Specification of Letters Patent.

Patented Apr. 20, 1920.

Application filed March 24, 1919. Serial No. 284,864.

To all whom it may concern:

Be it known that I, BEN F. FOWLER, a citizen of the United States, and a resident of Midian, in the county of Butler and State 5 of Kansas, have invented certain new and useful Improvements in Means of Sediment-Drainage, of which the following is a description, referring to the drawings, which form a part of this specification.

10 My invention relates to means for separating sediment and water from crude oil in storage tanks, and the object of the invention is to provide means by which this may be effected quickly and without removing 15 the oil from the tank.

As is well known crude oil contains a considerable quantity of foreign material of higher gravity than the oil. This falls as sediment in the tanks and reaches a depth 20 of two feet or more thus reducing the capacity of the tank, and by agitation tends to mix again with the oil. Moreover crude oil usually contains water, the presence of which in the tank is very undesirable.

25 My invention consists in providing a series of troughs upon the bottom of a tank, and at the bottom of each trough, means for discharging water and sediment to the outside of the tank, and it further consists in the 30 valve device and details of construction hereinafter noted.

In order that my invention may be better understood, reference will now be made to the accompanying drawings, in which—

35 Figure 1 is a sectional plan view of the tank provided with the preferred structure of the invention, a portion of the trough structure and portions of the valve sleeves being broken away. Fig. 2 is an elevation 40 of the upper part of the tank. Fig. 3 is a vertical section, taken on line 3—3 of Fig. 1, showing oil and sediment. Fig. 4 is a sectional detail of two of the discharge pipes and the intermediate inclines or trough 45 walls. Fig. 5 is a sectional detail showing one of the stuffing boxes.

A is the tank which may be of any preferred shape and of any suitable material, it comprises the staves 1 and a flat bottom 3, 50 which bottom is of any usual construction.

Upon each half of the bottom 3 is laid a series of V shaped troughs 4 which extend from the wall of the tank to the central line of the tank. As shown, each trough wall is 55 made of two boards or plates 4 which are

fastened to end pieces 5, their upper edge being secured to a center strip 6. The lower edges of the walls 4 rest upon valve sleeves 7, which are laid upon or close to the bottom of the tank. Each sleeve 7 passes out 60 through the wall of the tank and has a threaded end portion 7', to receive an inside nut 8 and an exterior stuffing box 9; in which 10 is the packing. Each sleeve 7 is thus held against rotation and leakage prevented. 65

The inner end of each sleeve 7 is closed by a cap 11. Each sleeve is provided with a row of upwardly opening ports 12.

Rotatably mounted in each of said sleeves 70 is a pipe or tube 13, which is provided with a series of ports 12. The pipes 13 pass out from the tank through the stuffing boxes 9 and may be provided with cut off valves 15 which also serve as handles by which the 75 pipes may be turned.

Referring again to Fig. 1 it will be noted that the inner ends of the longer troughs 4, above described, are downwardly inclined as shown at 16; the object of this being to form 80 a diametrical trough at right angles to said troughs 4. The diametrically arranged trough formed by the inclined ends 16 of the troughs 4 is provided with two vent pipes 17, each of which is inclosed in its non-rotatable sleeve 18, as shown at the left (Fig. 1) 85 having the ports 19.

In addition to the principal troughs which have been described, I have shown in Fig. 1 a number of shorter troughs, 20 and 21, 90 which cover the bottom space not served by the longer troughs. Some of these short troughs are parallel to troughs 4, while others are at right angles thereto. 22 indicates the sleeves at the bottom of the short 95 troughs 20; 23, the sleeve ports; 24, the outlet pipes thereof. 25 indicates the sleeves associated with short troughs 21; 26 the sleeve ports, and 27, the outlet pipes thereof.

The mode of operating the valves will be 100 obvious. Normally of course, all the pipes 13, 17, etc., are so turned that the sleeve ports 12, 19, etc., are closed, as shown at the left in Fig. 4. When it is desired to drain out the water and sediment, the pipes 13, 17, etc., 105 are turned until the valve ports register, as shown at the right, Fig. 4, and the outside valves 15 are opened. The sediment and water will flow out through the pipes, and at the proper time the valves 15 are closed 110

and the pipes turned back to hold the deposits out of the pipes until time for the next draining operation.

Having described my invention, I claim
5 and desire to secure by Letters Patent:

In a tank adapted to contain crude oil, sediment and water in combination, means for separating and removing said sediment and water from such combination comprising
10 a plurality of V-shaped troughs supported from the tank bottom and within which troughs said sediment and water are adapted to collect; a plurality of sleeves resting on the bottom of said tank, each sleeve registering with and supporting the base of one of said troughs; each of said sleeves extending through a stuffing box in the wall of
15

said tank, a plurality of ports in each sleeve upwardly opening to connect with its superposed trough, a pipe rotatably arranged 20 within said sleeve and stuffing box, ports in said pipe adapted to register with the ports in said sleeve and a valve on said pipe without the tank; the pipes within the sleeves being normally positioned so that the pipe 25 and sleeve ports do not register but when said pipes are rotated to occasion port registration and said valve is opened to allow for drainage of said sediment and water without the tank.

BEN F. FOWLER.
